United States Patent Office

Des. 218,725
Patented Sept. 15, 1970

218,725

SHAVER

John F. Daniels, Bridgeport, Conn., assignor to Sperry Rand Corporation, New York, N.Y., a corporation of Delaware

Filed Mar. 7, 1969, Ser. No. 16,125

Term of patent 14 years

Int. Cl. D28—03

U.S. Cl. D95—3

FIG. 1.

FIG. 2.

FIG. 3.

FIG. 4.

FIG. 5.

FIG. 1 is a front perspective view of a shaver showing my new design;

FIG. 2 is a rear elevational view thereof;

FIG. 3 is a side elevational view thereof;

FIG. 4 is a top plan view thereof; and

FIG. 5 is a bottom plan view thereof.

The dotted line features in the drawing are shown for environmental purposes only.

I claim:

The ornamental design for a shaver, substantially as shown and described.
